US0D1033114S

(12) United States Design Patent (10) Patent No.: US D1,033,114 S
(45) Date of Patent: * Jul. 2, 2024

(54) OVEN

(71) Applicant: FOSHAN OIMIS ELECTRICAL APPLIANCE & TECHNOLOGY CO., LTD., Foshan (CN)

(72) Inventor: Lijin Weng, Chaozhou (CN)

(73) Assignee: FOSHAN OIMIS ELECTRICAL APPLIANCE & TECHNOLOGY CO., LTD., Foshan (CN)

() Term: 15 Years

(21) Appl. No.: 29/826,527

(22) Filed: Feb. 14, 2022

(30) Foreign Application Priority Data

Dec. 24, 2021 (CN) 202130855066.X

(57) CLAIM

The ornamental design for an oven, as shown and described.

DESCRIPTION

FIG. 1 is a top perspective view of an oven, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines illustrate portions of the oven and form no part of the claimed design.

1 Claim, 8 Drawing Sheets
